UNITED STATES PATENT OFFICE.

DAVID P. MOORE, OF WASHINGTON, DISTRICT OF COLUMBIA.

FLUID-HYDROCARBON BURNER.

968,252.

Specification of Letters Patent. Patented Aug. 23, 1910.

Application filed October 3, 1908, Serial No. 456,016. Renewed April 28, 1910. Serial No. 558,284.

To all whom it may concern:

Be it known that I, DAVID P. MOORE, a citizen of the United States, residing at Washington, in the District of Columbia, 5 have invented certain new and useful Improvements in Fluid-Hydrocarbon Burners, of which the following is a specification, reference being had therein to the accompanying drawing.

10 This invention relates to improvements in fluid hydro-carbon burners, and has special reference to an improved form of burner, which is adapted to consume light, medium and heavy or crude oils, smokelessly and 15 with intense heat, thereby adapting itself for use in low pressure steam or air blast furnaces, or for use in cupola or glass furnaces.

To attain this end, my burner consists 20 primarily of a casting which is adapted to be inserted and held within the wall of the furnace, so that air or steam and oil are admitted exteriorly of the wall, and projected into and through the burner into the 25 furnace, the said burner being provided with an atomizer and an auxiliary atomizer, the combination of which, I find gives the best possible results in complete combustion and the direction of the blast.

30 To clearly illustrate my invention, attention is invited to the accompanying drawings, in which:—

Figure 1 is a side elevation of my burner in use in the wall of a furnace. Fig. 2 is a 35 longitudinal section through the burner. Fig. 3 is a section on line $x-x$, Fig. 2. Fig. 4 is a front elevation. Fig. 5 is a longitudinal section through a modified form of burner. Fig. 6 is a detail view of the 40 auxiliary atomizer as used in Fig. 5, and Figs. 7 and 8 are detail views of an adjustable oil nozzle.

Referring to the drawings:—A designates the wall of the furnace, in which is 45 “set” or secured the rectangular end B, of the casting or burner.

Projecting exteriorly of the wall and integral with B, is the tapered blast pipe attaching end 1. Provided longitudinally 50 of the casting is the tapered channel or bore 2, which is provided with the small entrance end 2^a, and the large exit end 2^b. In the upper portion of the reduced end of the casting or burner, I provide a threaded opening 3, in which is mounted the pipe 4 and nozzle support 5 and

the oil nozzle 6, being carried thereby. The central line of the nozzle is substantially the line $x-x$, of Fig. 2, and thus the oil under pressure, which is controlled by the valve 7, 60 is introduced through the nozzle 6, into the channel 2, of the burner.

Formed integral with the casting and depending by means of the support 9, is the ovoidal spreader or atomizer 8, the lowest 65 point of which is substantially on the line $x-x$. The open ring 10 or what I term the auxiliary atomizer, having its opening 11, toward the nozzle 6, has its axle or support 12, journaled in the reduced end of the casting, substantially on line $x-x$, the said axle being rotatable, so that the ring can assume various positions, as shown in full and dotted lines, Fig. 2. When this ring has been turned 70 at its proper or desired adjustment, the lock nut 13 is employed to retain and lock the axle against movement, the adjustment being accomplished entirely from the exterior 75 of the furnace.

In order to prevent the oil from flowing 80 backward into the blast pipe, when the blast is shut-off, or when more oil is delivered to the burner than can be at that time consumed, the dam 14, which is a small wedge-shaped portion with a straight edge toward the blast entrance and inclined toward the other end, is provided. I have also found it unnecessary on account of this dam 14, 85 to have the burner exactly on a horizontal line.

When it is desired to use light oils, the 90 diameter of the ring 10 is reduced, that is a smaller ring is used, the size increasing with the weight of the oil.

The burner just described is clearly shown 95 in Figs. 1, 2, 3 and 4, but in the modified form shown in Figs. 5 and 6, I displace the ring 10 with a grid or plate 10', having a series of tapered in cross section bars 11', 100 the said grid being vertically adjustable through the medium of the threaded supporting and adjusting medium 12'. By this means the grid is moved up or down in front of the nozzle 6, and thus acts in a similar manner to the ring 10.

The nozzle shown in Figs. 7 and 8, has a ball 6', carried upon the lower end of the pipe 5, and upon this ball, is adjustably mounted the globular casing 6'', which carries the nozzle or spout 6'''. In order to adjust this nozzle or spout and allow it to as- 110

sume the position shown in full and dotted lines Fig. 7, I employ the rod 6^a, which is journaled in the wall of the burner and has its operating knob 6^b, accessible from the exterior. To adjust the nozzle and cause it to assume the position shown in full or dotted lines, Fig. 7, the rod 6^a is turned or rotated slightly in its journal or the wall of the burner, this turning action causing the ball-and-socket joint of the nozzle to move, so as to project the nozzle in the direction desired, that is either toward the bottom or top of the burner or directly toward the atomizers. By this rod 6^a, the adjustment of the nozzle may be changed at pleasure.

The operation of my improved fluid hydro-carbon burner is about as follows:— The blast is introduced through the end 2^a, while the oil under pressure is introduced into the channel through the nozzle 6. The ovoidal spreader or atomizer and the open ring 10 or grid 10', serve to separate the oil stream and atomize it, the ring and grid being adjustable so as to regulate the direction of projection of the oil. Previous to the atomizing of the oil, a piece of waste saturated with oil, is thrown into the furnace, then ignited with flame, so that when the oil is properly atomized into the furnace, the same ignites at the mouth of the burner, and the flame is directed through the end 2^b, of the burner.

What I claim, is:—

1. In a burner, the combination of a casing having a tapered channel, means for delivering fluid hydro-carbon at the center line of said channel, a stationary atomizer mounted in said channel and having its lowest portion on said center line thereof, and an adjustable auxiliary atomizer intermediate of the delivering means and the stationary atomizer.

2. In a burner, the combination of a casing having a tapered channel, a fluid delivering pipe discharging the fluid at substantially the axial center of the channel, an atomizer having its lowest point in line with said axial center, and an auxiliary atomizer interposed between the discharge and the first mentioned atomizer.

3. In a burner, the combination of a casing having a tapered channel, a fluid delivering pipe discharging the fluid at substantially the axial center of the channel, an atomizer having its lowest point in line with said axial center, and an adjustable auxiliary atomizer interposed between the fluid discharge and the first mentioned atomizer.

4. In a burner, the combination of a casing having a blast and fluid conducting channel, a fluid discharge nozzle at the center line of said channel, an atomizer mounted in said channel near the discharge end

thereof and wholly above said center line 65 of the channel, and an auxiliary atomizer interposed between the fluid discharge and said first named atomizer.

5. In a burner, the combination of a casing having a blast and hydro-carbon fluid 70 conducting channel therethrough, a fluid discharge nozzle in said channel, an atomizer stationarily mounted in the channel near the discharge end thereof, and an open ring journaled in the channel intermediate 75 of the discharge and the atomizer.

6. In a burner, the combination of a casing having a tapering blast and hydrocarbon fluid conducting channel, a fluid discharge nozzle at the axial center of the 80 channel, a stationary atomizer having its lowest point in line with said axial center, a pivoted open ring interposed between the fluid discharge and the stationary atomizer, and means exterior of the casing for adjust- 85 ing said ring.

7. In a burner, the combination of a casing having a tapering blast channel therethrough, a fluid discharge nozzle detachably mounted in the channel near the smaller 90 end, a stationary atomizer depending from the upper portion of and within the channel near the larger end, an auxiliary atomizer mounted within the channel intermediate of the stationary atomizer and the 95 fluid discharge, and means operable from the exterior of the casing for adjusting said auxiliary atomizer.

8. In a burner, the combination of a casing having a tapering blast channel therethrough, the blast being admitted in the smaller end, a pipe for feeding fluid into said channel, a fluid discharge nozzle adjustably and detachably mounted upon said pipe within the channel near the smaller 105 end thereof, a stationary atomizer depending from the upper portion of and within the channel near the larger end, an auxiliary atomizer mounted within the channel intermediate of the stationary atomizer and the 110 nozzle, and means operable from the exterior of the casing for adjusting said auxiliary atomizer.

9. In a burner, the combination of a casing having a blast and hydro-carbon fluid 115 conducting channel therethrough, a fluid discharge nozzle in said channel, an open ring pivotally mounted within the channel and against which the fluid is discharged, and means exterior of the casing for adjust- 120 ing said ring.

In testimony whereof I affix my signature in presence of two witnesses.

DAVID P. MOORE.
